UNITED STATES PATENT OFFICE

EDWIN C. HAMILTON, OF SOMERVILLE, MASSACHUSETTS, ASSIGNOR TO G. LANZA
DAVISON, OF WINTHROP, MASSACHUSETTS.

DROP-HAMMER.

1,171,718.

Specification of Letters Patent. Patented Feb. 15, 1916.

Application filed July 6, 1914. Serial No. 849,079.

To all whom it may concern:

Be it known that I, EDWIN C. HAMILTON, a citizen of the United States, and resident of Somerville, in the county of Middlesex 5 and State of Massachusetts, have invented certain new and useful Improvements in Drop-Hammers, of which the following is a specification.

The present invention relates to machines 10 of the drop hammer or drop press type in which a weight is withdrawn by power from an anvil and is thereafter released from the actuating means and allowed or caused to approach the anvil by the force of gravity, or of a spring, or both.

The invention is particularly concerned 15 with means for preventing a second blow of the hammer after the inevitable rebound thereof upon the first stroke, and with an improved mechanism for effecting withdrawal of the hammer from the anvil preparatory to the making of a working stroke.

The objects of the invention therefore are 20 to provide an improved form of mechanism which shall be positive and certain in its operation and capable of arresting the hammer after rebound thereof at the point where the rebound ends, wherever such point may be; and to provide a compact mechanism for 25 actuating the hammer previous to the automatic drop thereof, having parts capable of being interchanged with similar parts of different dimensions for enabling as great a stroke to be given the hammer as may be 30 required without making any part of the mechanism objectionably bulky. The manner in which I have accomplished these objects is fully set forth in the accompanying 35 specification.

In the drawings forming a part of the 40 specification, Figure 1 is a side elevation of so much of a drop hammer in which I have embodied my invention as is necessary to illustrate that part of the invention which resides in the hammer actuating mechanism. 45 Fig. 2 is a front elevation of so much of the hammer as is illustrated in Fig. 1. Fig. 3 is a front elevation on an enlarged scale of a part of the hammer, and of the means 50 which forms a part of the invention for securing the hammer on the rebound and preventing a second stroke thereof. Fig. 4 is an elevation of the re-bound catcher at the left hand side of the hammer, showing the

same and the associated parts in a different 55 position from that shown in Fig. 3. Figs. 5 and 6 are horizontal sectional detail views taken on lines 5—5 and 6—6, respectively, of Fig. 3.

The same reference characters indicate the 60 same parts in all the figures.

Referring to Figs. 1 and 2 for an illustration of the machine as a whole and of the mechanism for elevating the hammer, the base of the machine is represented at 10. 65 Such base, of which only the upper part is shown in the drawings, may be of any desired construction, and it supports an anvil 11, which latter is centered by screws 12, 12, 13, 13 contained in uprights 14, 14 and 70 15, 15, respectively, and so arranged as to engage the four sides of the anvil. The base 10 supports a frame consisting of two uprights 16, 16 and a transverse beam 17 at the top. Said uprights constitute guide- 75 ways and guide the hammer weight or weighted hammer 18, which has ribs 19 shown in Figs. 5 and 6, at each side contained in the longitudinal guide grooves of the guide bars or ways 16, 16. The hammer 80 head, or hammer proper, 20 is mounted in the lower end of the weight 18, as shown in Fig. 2 and projects therefrom toward the anvil. The weight 18 and hammer head 20, together constitute the hammer, but for convenience of description I prefer to apply 85 distinguishing terms to these two elements.

The mechanism for lifting the hammer comprises a slide 21, which I may term for convenience of description, a hammer lifter, 90 which travels between the bars 16, 16 in guideways 22 thereof behind and parallel to the guideways in which the hammer weight 18 travels as shown in Fig. 1. Said hammer lifter is hung by a cable 23, which 95 passes around and is secured to a drum 24. Said drum is secured on a shaft 25 mounted in bearings 26 on brackets 27, which are attached to or form part of the bar 17. The shaft 25 also carries gear pinions 28 on opposite sides of the drum 24, which pinions mesh with the teeth of rack bars 29. Said rack bars pass between the pinions, with which they respectively engage, and the 100 guide rolls 30 mounted on studs which are 105 carried by lugs 31. The two rack bars are connected together at their lower ends and are secured to a rod 32 which has a connec-

tion with a crank disk 33 through a crank pin 34. Crank disk 33 is mounted on a shaft 35 whereon there rotates loosely a gear wheel 36 driven by a pinion 37 on a shaft 38 to which is also connected a pulley 39. A clutch 40 and a clutch operating lever 41 are provided for connecting the gear wheel 36 to the shaft 35 wherever it is desired to operate the machine. Any suitable clutch and clutch operating mechanism may be used for this purpose, but I prefer one of the type which is automatically disconnected upon the completion of one rotation of the gear 36 and shaft 35 after being connected.

It will be understood that the rotation of the crank disk 33 causes the racks 29 to be raised and lowered, thereby rotating the cable drum 24 first in one direction and then in the opposite direction, raising and lowering the hammer lifter 21. The mechanism just described constitutes the hammer lifting mechanism and is one of the features of my present invention. Said mechanism is simple and positive and may be proportioned to give any desired lift to the hammer without being made objectionably bulky, and particularly without requiring the crank which operates the racks to be made unduly long. The pinion 28 and drum 24 may be readily removed to permit substitution of another group of similarly arranged elements of greater or smaller diameter, or for substitution of other pinions only. It is evident that by thus replacing either the pinions 28 or the drum 24, or both, by other pinions and another drum of greater or smaller diameter, the extent of travel of the hammer lifter can be altered without changing the stroke of the racks. An important feature is this, that the operating mechanism provides a means by which as great a lift as may be required may be given to the hammer without making the crank disk 33 or the length of the crank arm unduly great.

The mechanism which is shown here for coupling the lifter to the hammer and then tripping the connection is not my invention, but is essentially the same as that described and claimed in the patent to S. H. Dyer, No. 1,082,685 granted December 30, 1913. The adaptation of such mechanism embodied in the present machine involves a deg 42 pivoted to the lifter 21 and thrown outwardly by spring 43, so arranged as to cause the dog to pass under a shoulder 44 in the rear of the hammer weight 18 when the slide is lowered. A pin 45 passes through the hammer weight from front to rear and is beveled or tapered at its front end 46. It lies just below the shoulder 44. A lever 47 is pivoted to the front side of the hammer weight at 48 and passes above the beveled end of the pin 45. Said lever has an arm

49 extending across one of the upright bars 16 in position to strike a stop 50, which projects forwardly from said bar, when the hammer is raised. Stop 50 may be placed in any one of a number of holes 51. When the lifter 21, after having been coupled to the hammer, is raised, it raises the hammer until the arm 49 strikes the stop 50, when the lever 47 is arrested. The relative movement between the lever and the hammer due to the continuing rise of the latter, causes the lever to wipe across the beveled end of the pin 45 and to force said pin rearwardly against the dog 42, pushing the dog out of engagement with the shoulder 44 and leaving the hammer unsupported, whereupon the hammer drops. By placing the stop 50 in different positions, the hammer may be given a longer or shorter extent of upward travel before being released, and thus the force of the blows which it delivers may be regulated. It is to be noted that the length of the hammer stroke may thus be altered without requiring any change in the extent of travel given to the hammer lifter.

A spring 52 is provided for applying pressure to the hammer and adding to the effect of gravity. The form of spring here shown is a helical spring of which the lower end embraces a stud 53 on the hammer weight, and the upper portion passes through an opening in the bar 17 and is contained in a housing 54, which is secured to the upper side of the said bar. The spring is compressed whenever the hammer is raised and when the hammer is released its force is applied to actuate the hammer. The employment of the spring makes it unnecessary to provide for so great a drop in order to secure a blow of given force as would be the case if the spring were not present, and the spring makes the action of the hammer more rapid than would otherwise be the case.

A hammer of the sort described, unavoidably rebounds after striking the work on the anvil, and it is necessary to provide means for arresting the hammer on the rebound to avoid an objectionable second blow. I have provided an improved means for catching the hammer on the rebound, which constitutes another portion of my invention. The description of this means for catching the hammer, or rebound catcher, follows:

Secured to the hammer weight at the forward side near the edges thereof are toothed bars 55 which preferably project somewhat over the adjacent upright guide bars 16. These toothed bars have teeth 56, the under sides of which are approximately horizontal and the upper sides of which are downwardly inclined. Such teeth are thus similar to ratchet teeth, wherefore for the purposes of this description I will designate the bars 55, ratchet bars and the teeth 56 ratchet

teeth. Co-acting with each of said ratchet bars is a complementary clutch block 57 having upwardly inclined teeth 58 of such size and spacing as to be capable of interlocking with any of the teeth 56. The clutch blocks and the mechanisms for operating them which I have provided at each side of the machine are duplicates of one another and a description of one will suffice for both.

5 The clutch block is mounted so that it may slide horizontally in a bearing plate or guide 59 which is secured to the forward side of the upright guide bar 16. For the purposes of this description I will call the member 59 a transverse guide, meaning by this term that said guide is arranged to limit the movement of the clutch block to a direction transverse to that in which the hammer travels, and without intending otherwise to limit the said guide in respect either to its form, direction, or location. The clutch block carries a pin 60 which projects through a slot 61 in the transverse guide 59 and enters a slot 62 in a lever 63 which is pivoted by a stud 64 to the upright guide 16. Said lever 63 is provided with a forwardly projecting rib 65 having an inclined cam surface 66 at its lower end, and a surface 67 on the side toward the hammer. The said surfaces 66 and 67 meet at an edge which is sufficiently fine for my purposes. Fixed to the hammer weight above the ratchet bar 55 is a bracket 68 which projects across the guide bar 16 and the lever 63. In the bracket 68 is a transversely movable rod or slide 69 located in front of the rib 65 and carrying a stud 70 which projects toward the upright guide bar 16 sufficiently far to engage the rib 65. Stud 70 is preferably formed with its opposite faces inclined, and beveled or rounded, the inclination of such faces being downward and inward, and the opposite faces meeting in sufficiently fine edges. A spring 71 is attached at one end to

30 a pin 72 which is connected to the slide 69, and at its other end to a pin 73 attached to the bracket 68. The spring tends to draw slide 69 toward the center line of the machine. The movement of the slide in this direction is limited by shoulder 74 on the slide and a complementary shoulder 75 on the bracket.

35 A leaf spring 76 is mounted in a pin 77 and engages the end of the lever 63, being arranged, and operating, to place said lever in the position shown in Fig. 4, when the lever is otherwise free and unobstructed.

40 The operation of the rebound catcher above described may now be understood.

45 When the hammer falls, after having been raised by the lifter 21 and tripped, the stud 70 passes down along the surface 67 of the rib 65, being held by the spring 71 and the shoulders 74 and 75 in the location which

50 enables it to pass on that side of the rib.

Thus the stud pushes the lever 63 and the clutch block 57 outwardly, and provides a clear path without obstructions for the descent of the hammer. As soon as the stud 70 has passed the lower end of rib 65, the spring 76 returns the lever to normal position, in which the lower end of the cam surface 66 is above and somewhat to the right of the upper edge of the stud, as shown by the dotted line position 70^a in Fig. 4. 75 That is, the lower end of the beveled surface is nearer the center line of the machine than is the uppermost edge of the stud. In consequence when the hammer rebounds after striking the anvil, the stud rides up on the inclined surface 66, throwing the lever 63 and clutch block 57 toward the ratchet bar 55. The teeth of the bar then slip past the teeth of the block, the spring 71 yielding sufficiently to permit this, and at the same time constantly pressing the block toward the ratchet bar, so that as soon as the momentum of the hammer is exhausted and it starts to fall, the teeth of 55 and 57 will interengage and prevent it from falling. 80 The dimensions of the parts, including the length of the ratchet bar and of the rib 65 are preferably such that the momentum of the greatest rebound will become exhausted before the stud 70 passes beyond the upper 85 end of the rib 65, and before the ratchet bar passes entirely beyond the upper end of the clutch block 57. 90

95 As a result of there being a large number of teeth on the ratchet bar and clutch bar, 100 it follows that under all conditions, except the extreme one, which is not expected to happen in practice, when the hammer passes entirely beyond the clutch block on the rebound, several of the complementary teeth on 105 the ratchet and clutch will become interengaged at the same time, thereby holding the hammer with security. It follows also that, after reaching the limit of rebound, the hammer can not fall more than the distance 110 of one tooth space before being caught, so that it is arrested after the rebound practically without shock. These circumstances together make it impossible for the teeth to be stripped. 115

The mechanism above described for arresting the hammer on the rebound is positive and certain in operation, and free from liability to accident. On the descent of the hammer when making a stroke, the stud 70 120 is rigidly held by the shoulders 74 and 75 so that it must cause displacement of the clutch block out of the path of the ratchet bar, whereby interference between the ratchet and clutch is made absolutely impossible. On the rebound of the hammer the stud is certain to place the clutch block in arresting position, owing to the spring 76, which is free to act as soon as the hammer ends its stroke, and to the engagement which 125 130

is thereby unavoidable between the stud 70 and the cam surface 66. Thereby the clutch block is certainly and surely put into position for engaging the ratchet teeth, but not 5 into such rigid engagement as to prevent upward movement of the hammer and to risk danger of injuring the teeth on the ratchet or the clutch, because the spring 71 permits yielding of the clutch; and as soon 10 as the hammer begins to descend after the rebound, it is caught before it has had time to gain any momentum.

I am aware that heretofore devices have 15 been provided for catching a trip hammer on the rebound and preventing the hammer from making a second blow, but so far as I am aware none of such devices has contained a means for positively preventing operation 20 of the rebound catcher during the striking travel of the hammer, nor has contained mechanism which is certain to work under all circumstances for bringing the arresting device and the mechanism into operative condition at the proper time.

25 I desire to state that I do not limit the invention to the precise details of construction, arrangement, and operation hereinbefore described, as wide variations in such features may be made without departing 30 from the spirit of the invention as claimed.

The terms denoting verticality and horizontality used in this specification and those 35 denoting relative heights and directions are not intended as limiting terms, but are used solely as descriptive terms with respect to the embodiment of the invention here illustrated.

What I claim and desire to secure by Letters Patent is:

40 1. In a drop hammer the combination with a hammer and means for guiding the same, of complementary ratchet and clutch elements connected with the hammer and guide respectively, and positive means connected to the hammer and the clutch element respectively, arranged to come into engagement with one another during the working stroke of the hammer for holding said ratchet and clutch elements out of connection during such stroke said means being operative for bringing said elements into co-operation on the rebound of the hammer.

45 2. In a drop hammer the combination with a guiding element and a hammer arranged to travel along said element, a ratchet block carried by the hammer, a complementary clutch block mounted on the guiding element and movable in a direction transverse to the movement of the hammer, positively acting means for moving and holding 50 said block away from said ratchet during the descent of the hammer, means for automatically returning the clutch to normal position when the hammer has completed its stroke, and means automatically operated by

the hammer for moving said clutch into engagement with the ratchet on the rebound of the hammer.

3. In a drop hammer the combination with a hammer and a guiding element, of a ratchet carried by the hammer, a clutch block mounted on the guiding element, a cam device connected with the clutch element, and a clutch actuator carried by the hammer and arranged to act upon said cam device to hold the clutch element away from the ratchet during the working stroke and to hold the clutch element against the ratchet in the subsequent rebound of the hammer.

4. In a drop hammer the combination of a frame and a hammer element arranged to travel upon said frame, complementary ratchet and clutch elements, one of which is mounted on the hammer and the other of which is mounted on the frame, and one of which is further movable toward and away from the other, a cam member connected with said movable element, and an actuator operated by the relative movement between the hammer and frame for engaging said cam member on one side during the descent of the hammer, said actuator being constructed and actuated to cause a positive separation between the ratchet and clutch elements throughout the travel of one element past the other, and to engage the other side of said cam member yieldingly on the rebound of the hammer, so as to bring said elements into engagement.

5. In a machine of the character described, the combination of a stationary guide and a moving hammer member, a ratchet element and a complementary clutch element, each of said elements having a plurality of co-operating teeth, one of said elements being carried by the hammer and the other being mounted on the guide, and one of said elements being movable toward and away from the other, and means operated by the movement of the hammer for holding said elements apart with a positive action during the working stroke of the hammer and for bringing said elements into engagement in a yielding manner upon the rebound of the hammer.

6. In a drop hammer the combination of a hammer member, a guide therefor, a ratchet block, a complementary clutch block movable transversely to the movement of the ratchet block, one of said blocks being carried by the hammer and the other mounted on the guide, a cam connected with said clutch block and having cam surfaces at opposite sides and a clutch actuator movable with the hammer member and arranged to engage the surface at one side of said cam when moving in one direction and engage the surface at the opposite side of the cam when moving in the opposite direction, whereby the clutch block is first positively moved away from the ratchet

block and is then brought into engagement with the latter.

7. In a machine of the character described, the combination of a hammer, a stationary frame, complementary clutch members connected to the hammer and frame respectively, one of said clutch members being movable toward and away from the other, a cam connected to said movable clutch member and having oppositely disposed cam faces, a cam actuator operable by movement of the hammer relatively to the frame arranged to engage one of said faces during the operative stroke of the hammer, and means for causing the actuator to engage the opposite face during the rebound of the hammer.

8. In a drop hammer the combination of a hammer and a frame, a ratchet bar carried by the hammer, a clutch block mounted on the frame and guided to move toward and away from said ratchet bar, a cam rib movable in approximately the same directions as said block and connected therewith, an actuator carried by said hammer arranged to engage one side of said rib during the working stroke of the hammer, and means for shifting said block at the end of said stroke, whereby said actuator is caused to engage the opposite side of the rib on the rebound of the hammer.

9. In a drop hammer, the combination with a hammer and a frame on which the hammer is guided, of a ratchet bar having a plurality of teeth carried by the hammer, a complementary clutch block having a plurality of teeth, mounted on the frame, means for preventing in a positive manner engagement of said ratchet bar teeth with clutch block teeth during a working stroke of the hammer, and means for resiliently holding the ratchet bar and clutch block in engagement during the rebound of the hammer, whereby the hammer is arrested at any point to which it may rebound and is prevented from moving appreciably after the rebound.

10. In a drop hammer, a hammer member, means for guiding the same in a predetermined path, coöperating ratchet and clutch elements, one of said elements being carried by the hammer member and the other being mounted on the guiding means and being movable transversely of the direction in which the hammer member travels, said elements having teeth adapted to interengage upon rebound of the hammer member after a blow, a cam associated with the transversely movable clutch element, and a cam actuator carried by the hammer member, said cam actuator being movable transversely of the hammer travel and being yieldingly urged in one direction, and having a positive abutment to limit its movement in that direction, the said actuator when in the position thus limited being ar-

ranged to engage the cam member on the down stroke of the cam and displace the clutch element from the ratchet element, the cam member having a surface arranged to engage the opposite side of the cam actuator on the up stroke of the hammer and displace the actuator against said yielding means, the yielding means then acting to urge the clutch element yieldingly toward the ratchet element.

11. In a drop hammer, the combination with a hammer member and means for guiding the same in a definite path, a stop carried by said member, a complementary clutch mounted on the guiding means movable into and out of engagement with said stop, and actuating means carried by the hammer for controlling said clutch, said actuating means being constructed to hold the clutch away from the stop on the working stroke of the hammer and having a rigid abutment for causing positive action thereto, and yielding means tending to hold said actuator against the stop but permitting displacement away from the stop, whereby said actuator may act yieldingly on the rebound of the hammer to urge the clutch toward the stop.

12. In combination with a drop hammer and means for guiding the same, said hammer and guiding means having interengageable clutching elements for arresting the hammer on the rebound thereof, a means for controlling the one of said elements which is mounted on the guiding means and is movable toward and away from the path of the other of said elements, said controlling means comprising a cam engaged with said movable element and having opposite faces converging to a point at its lower end, an actuator carried by the hammer and movable transversely with respect thereto, a spring acting on said actuator in the direction from the transversely movable to the hammer-carried-clutch element, and a positive abutment for limiting the movement of said actuator in said direction, the said actuator being so limited in the position wherein it is caused during the working stroke of the hammer to engage said cam on the side thereof toward which the transversely movable clutch element must be moved for operation, whereby to hold said clutch element out of operative position.

13. In a drop hammer in combination with a hammer member and a guide therefor, a clutch element carried by the hammer, a complementary clutch element carried by the guide, one of said elements being movable transversely to the direction of movement of the hammer, a cam connected to said transversely movable element and an actuator carried by the hammer and adapted to engage said cam, said actuator

being positively controlled to hold the transversely movable clutch away from the complementary clutch element during the driving stroke of the hammer, and being 5 yieldingly urged to press the transversely movable clutch toward the complementary clutch upon the rebound of the hammer.

14. In a drop hammer the combination with a hammer member and a hammer lifter of a cable by which said lifter is hung, a drum on which said cable is wound, a gear wheel connected with said drum, a rack meshing with said gear wheel, and a crank and connecting rod connected with 15 said rack, whereby the latter is given a reciprocating movement.

15. In a drop hammer, a hammer lifting mechanism comprising a rotary driving element, a cable drum, a hammer lifting cable 20 depending from said drum and secured thereto, and intermediate mechanism for imparting an oscillative movement to said drum from the continuous rotation of the driving element.

25 16. A hammer lifting mechanism comprising a rotary driver, a crank pin carried by said driver, a cable drum, transmission mechanism between said crank pin and cable drum constructed to give an oscillating movement to the latter, and a hammer

lifting cable attached to and depending from said drum.

17. A drop hammer comprising in combination a frame, a hammer guided for movement upon said frame, a hammer lifting cable, a drum to which said cable is attached and about which it is wrapped, a pinion having a smaller diameter than said cable, a rotary driver having a crank pin, a connecting rod engaged with said crank pin, and a rack rigid with said connecting rod and meshing with said pinion. 35

18. In a drop hammer, the combination of a rotary driving crank, a cable drum, a connection from said crank to said cable 40 drum for permitting oscillating movement to the latter, a cable connected to said drum, a hammer, means for coupling said hammer to said cable, means for causing automatic disconnection of the hammer from the cable 45 during the rising movement of the hammer, and mechanism for arresting the hammer at the conclusion of its rebound after making the working stroke.

In testimony whereof I have affixed my 55 signature, in presence of two witnesses.

EDWIN C. HAMILTON.
